UNITED STATES PATENT OFFICE.

C. B. HURXTHAL AND JOHN LEE, OF BOLIVAR, OHIO.

GATE.

Specification of Letters Patent No. 30,223, dated October 2, 1860.

To all whom it may concern:

Be it known that we, CHARLES HURXTHAL and JOHN LEE, of Bolivar, Tuscarawas county, in the State of Ohio, have invented 5 certain new and useful Improvements in Self-Acting Gates; and we do hereby declare that the following is a full and exact description thereof, reference being had to the accompanying drawings and to the letters of reference marked thereon.

In the drawings: Figure is a perspective view of the gate as it appears when closed—the red lines showing it when opened, or raised. Fig. 2 is a side view of the gate, half 15 raised.

To enable those skilled in the art to make and use our invention, we will describe its construction and operation.

In the drawings, similar characters refer 20 to like parts.

A and A' are the gate-posts. B the back slat to which the horizontal slats C are attached. C' the horizontal slat, operated by spring a, and acting as a bolt or catch for 25 fastening the gate. D the front and middle inclined slats. It will be seen that the upper slat C extends out beyond the back-slat B a distance equal to the height of the gate, and is made of heavier timber than the 30 other slats. b a balance weight hung to the outer end of upper rail C. This weight is hung in such a manner as prevents the gate from opening violently, and enables it to start back easily. This weight is oblong in 35 shape, having its point of support nearer one end than the other. By this arrangement, the effect of the weight in balancing the gate is greatest at the time the gate begins to rise, and decreases as it is completely 40 raised.

c are wire rods attached to latch-slat C' and operating levers E, and also serve as braces to prevent sagging of the gate. E 45 operating levers. F the main pivot upon which the gate swings. This pivot is secured to upper slat C, and has its journal box or bearings in the main gate post A. On its ends are hooks or eyes d so that it can be readily attached to the levers E.

50 e are short arms on operating levers E, and have the latch-rods c attached to them. f, arms of levers E which the hand grasps

and elevates or depresses in opening or closing the gate.

g is a small wire or cord depending from 55 arms f, to be pulled for closing the gate, if it should be inconvenient to reach up to the arm f. G the lever-posts, at such distance from the gate, that it can be opened by one seated in a passing carriage. 60

The inclined back slat B is secured to the main-post A. The horizontal slats C are attached by bolts to slats B and D, working loosely upon said bolts so as to readily fold up. The latch-slat C' is slotted so that it 65 can slide laterally upon its bolts, as is required in bolting and unbolting the gate.

In operating our invention, as one approaches the gate in his carriage, he extends his hand, and grasping handle f throws it up 70 by the exertion of a few pounds of power; as this crank arm or lever f goes up, arms e at the other end of the operating lever E operate rods c, thereby unlatching the gate by sliding back the latch-slat C; at the same 75 time, operating lever E, by its attachment to main pivot F throws up the balance gate the slats of which fold up, and assume a vertical position as indicated by red lines in Fig. 1. In this position the gate would 80 remain until depressed or closed. The carriage now goes through the gate; as it comes to the other lever-post G, the driver extends his hand, and grasps the crankhandle f, or the depending rod g, and by depressing it, 85 completely reverses the process of opening the gate, and closes it firmly, throwing latch-slat C into its mortise.

Having thus fully described the construction and operation of our invention, what 90 we claim as new, and desire to secure by Letters Patent, is—

The arrangement of the inclined standard B, slats C, and C', spring a, levers E, and fixed bearing F and weight b the whole 95 operating as set forth.

C. B. HURXTHAL.
JOHN LEE.
